(57) **CLAIM**

The ornamental design for a chair, as shown and described.

DESCRIPTION

FIG. 1 is a front view of a chair according to the present invention.

FIG. 2 is a rear view of the chair of FIG. 1.

FIG. 3 is a left side view of the chair of FIG. 1.

FIG. 4 is a right side view of the chair of FIG. 1.

FIG. 5 is a top view of the chair of FIG. 1.

FIG. 6 is a bottom view of the chair of FIG. 1.

FIG. 7 is a top right perspective view of the chair of FIG. 1; and,

FIG. 8 is a bottom left perspective view of the chair of FIG. 1. In the drawings, the broken lines depicting seat, arm and base components of a chair form no part of the claimed ornamental design.
